UNITED STATES PATENT OFFICE.

FREDERICK GOERTZ, OF NEWARK, NEW JERSEY, ASSIGNOR TO THE SCOBAN COMPANY, INC., OF NEW YORK, N. Y., A CORPORATION OF NEW YORK.

SMOKER'S POUCH.

1,317,571.

Specification of Letters Patent. Patented Sept. 30, 1919.

Application filed January 28, 1919. Serial No. 273,626.

To all whom it may concern:

Be it known that I, FREDERICK GOERTZ, a citizen of the United States, and a resident of Newark, in the county of Essex and State 5 of New Jersey, have invented a new and Improved Smoker's Pouch, of which the following is a full, clear, and exact description.

My invention has for its object to provide a smoker's pouch having a body which is 10 normally closed by a head slidably disposed in an open end of the body, there being means to prevent the complete removal of the head under normal conditions, although permitting the withdrawal of the head 15 a sufficient distance to enable the user to obtain a cigarette paper and matches from compartments in the head, and also to expose an opening in the body through which tobacco may be fed.

20 Additional objects of the invention will appear in the following specification in which the preferred form of my invention is described.

In the drawings similar reference characters refer to similar parts in all the views, in which—

Figure 1 is a perspective view illustrating my invention, parts being broken away to show the construction;

30 Fig. 2 is a side elevation, partially in section, showing the head removed from the body;

Fig. 3 is an enlarged sectional view on the line 3—3 of Fig. 2; and

35 Fig. 4 is an enlarged sectional view on the line 4—4 of Fig. 2.

By referring to the drawings, it will be seen that the smoker's pouch is provided with a body 5, having an open end 6, in 40 which there is disposed a metal neck 7. The body 5 is preferably of such a shape that it may be conveniently disposed in a rear pocket.

In the body 5, and extending through the 45 metal neck 7, there is an outlet 8; the said outlet being disposed adjacent the open end 6 of the body, as best illustrated in Fig. 2 of the drawings. A head 9 is normally disposed in the metal neck 7, which serves to 50 close the outlet 8.

In the head 9, there are mounted pins 10 which extend through orifices 11 in the head, and which are adapted to be disposed in orifices 12, which are situated nearer the open 55 end 6 of the body 5 than is the outlet 8.

These pins 10 are held yieldingly outwardly by springs 13, so that when the user draws the head 9 outwardly relatively to the body 5, the pins 10 will be pressed outwardly by the springs 13 into the orifices 12 to lock the 60 head 9 relatively to the body 5 in the position shown in Fig. 1 of the drawings. In this position the head 9 has uncovered the outlet 8, so that the tobacco in the body 5 may be fed through the outlet 8. When the user 65 desires to fill the body 5 with tobacco, he presses inwardly the thumb pieces 14, which extend through openings 15 in the head 9, and which are connected with the pins 10, so that by this means the pins 10 may be drawn 70 inwardly out of the orifices 12 to permit the convenient removal of the head 9 from the body 5. The tobacco may be then poured into the body 5, after which the head 9 may be replaced in position by pressing inwardly 75 the thumb pieces 14, which will permit the pins 10 to pass the orifices 12.

In one side of the head 9, there is a compartment 16 in which cigarette papers may be disposed, this compartment 16 being partially inclosed by a wall 17 which serves to hold the cigarette papers in position. At the other side of the head 9, there is a compartment 18 in which matches may be disposed, this compartment 18 being normally closed 80 by a lid 19 which is provided with a spring hinge 20 which serves to hold the lid 19 normally closed, as shown in the full lines in Fig. 4 of the drawings. In this lid 19, there is a recess 21 in which may be disposed a 85 piece of material against which the matches may be struck.

It will be understood that the smoker's pouch will not only contain the tobacco, cigarette papers and matches, but these will 90 be carried in such form that they may be removed as may be desired without unnecessarily exposing the contents of the pouch, and this is so, although the pouch may be completely opened whenever necessary, so 95 that it may be conveniently refilled.

Having thus described my invention, I claim as new and desire to secure by Letters Patent:

1. In a smoker's pouch, a body having an 105 open end, and with an outlet in its side adjacent the open end, a head telescoping with the open end of the body for closing the outlet, and adjustable means to check the outward movement of the head relatively to 110

the body while an end of the head is disposed in the body.

2. In a smoker's pouch, a body having an open end and with an outlet in its side, a head telescoping with the open end of the body for closing the outlet, and means adapted to be freed at the will of the user to limit the outward movement of an end of the head beyond a point between the outlet 10 and the open end of the body.

3. In a smoker's pouch, a body member having an open end and with an outlet in its side, a head telescoping with the open end of the body member for closing the outlet, there being orifices in one of the members, pins mounted on the other member for movement into the orifices, resilient means for holding the pins yieldingly extended in operative position, and thumb pieces connected with the pins for pressing them into 15 inoperative position.

4. In a smoker's pouch, a body having an open end and with an outlet in its side, a head slidably disposed in the open end of the body, there being orifices in the body beyond the outlet, pins mounted adjacent the inner end of the head for movement into the orifices, resilient means for holding the pins yieldingly extended in operative position, and thumb pieces connected with the pins for pressing them into operative position, the thumb pieces being disposed between the pins and the other end of the head, so that they will be exposed when the pins 30 are disposed in the orifices.

5. In a smoker's pouch, a body member having an open end, a head telescoping with the open end of the body member for closing the outlet, there being orifices in one of the members, pins mounted on the other member for movement into the orifices, resilient means for holding the pins yieldingly extended in operative position, and thumb 40 pieces connected with the pins for pressing them into operative position, the thumb pieces being disposed between the pins and the other end of the head so that they will be exposed when the pins are disposed in the orifices, and means in the head for carrying cigarette papers and matches.

pieces connected with the pins for pressing them into inoperative position.

6. In a smoker's pouch, a body member having an open end, a head slidably disposed in the open end of the body, there being orifices in the body beyond the outlet, pins mounted adjacent the inner end of the head for movement into the orifices, resilient means for holding the pins yieldingly extended in operative position, and thumb pieces being disposed between the pins and the other end of the head so that they will be exposed when the pins are disposed in the orifices.

7. In a smoker's pouch, a body member having an open end and with an outlet in its side, a head telescoping with the open end of the body member for closing the outlet, there being orifices in one of the members, pins mounted on the other member for movement into the orifices, resilient means for holding the pins yieldingly extended in operative position, thumb pieces connected with the pins for pressing them into inoperative position, and means in the head for carrying cigarette papers and matches.

8. In a smoker's pouch, a body having an open end and with an outlet in its side, a head slidably disposed in the open end of the body, there being orifices in the body beyond the outlet, pins mounted adjacent the inner end of the head for movement into the orifices, resilient means for holding the pins yieldingly extended in operative position, thumb pieces connected with the pins for pressing them into operative position, the thumb pieces being disposed between the pins and the other end of the head so that they will be exposed when the pins are disposed in the orifices, and means in the head for carrying cigarette papers and matches.

FREDERICK GOERTZ.
